POWER SUPPLY

George D. Hulst, Upper Montclair, N. J., assignor
to Allen B. DuMont Laboratories, Inc., Passaic,
N. J., a corporation of Delaware

Application August 3, 1949, Serial No. 108,323

6 Claims. (Cl. 321—32)

1

This invention relates to power supplies for use with cathode ray apparatus and the like, and more particularly to power supplies for use in a television receiver.

In a television receiver, the second anode of the cathode ray tube which provides the accelerating force for the electron beam, is connected to a power source producing a positive direct potential of between 10 and 25 kilovolts, the higher voltages being in general more satisfactory for larger diameter and brighter picture tubes.

Voltage supplies producing this order of voltage usually have employed high voltage insulators cast from a special electrical ceramic material such as porcelain or glass. Such materials are not, however, adaptable for use in a television receiver because of their brittle nature. For this reason, plastic materials have been used as insulators for high voltage supplies in television receivers. Of these plastic materials, the most useful ones for the purpose have been thermosetting plastics, such as phenolics. Phenolics have excellent mechanical properties, do not exhibit cold flow, can be coated to prevent surface leakage, are inexpensive, and are easily molded or machined. Nevertheless, in spite of these desirable properties, the phenolics have not been used as high voltage insulators generally in high quality receivers, because of their tendency to carbonize in high voltage gradients and become conductive, causing eventual breakdown of the insulator and making the receiver inoperative.

It is an object of my invention to provide high voltage apparatus for use in a television receiver which completely prevents the carbonization of phenolic insulators.

It is a second object to provide apparatus which is inexpensive to produce, and which lends itself readily to manufacturing processes.

It is a further object to provide a structure which allows a voltage gradient of 10 kilovolts per inch in a phenolic insulator, permitting a compact and mechanically rigid arrangement of high voltage parts.

In the drawings:

Figure 1 shows schematically a circuit incorporating the invention;

Figure 2 is a side view of an embodiment with a portion broken away to show the construction; and

Figures 3, 4 and 5 show electrical fields and physical characteristics to illustrate the operation of the invention.

2

Referring to Figure 1, a transformer 12 has its primary winding connected between a source 13 of positive potential and the anode of a rectifier tube 14. A driving tube 15, having a signal grid 16, is connected to a tap on the primary winding. The secondary winding of the transformer 12 is connected to a filament type thermionic cathode of the rectifier tube 14 through the resistor 17. One side of the filament 18 is connected to a filter capacitor 19, to a filter resistor 19, and to a conductive member 21 constructed preferably cup-shaped in accordance with my invention. The other end of the resistor 19 is connected to a second filter capacitor 22 and to a high voltage output lead 23 which, in the preferred application, is connected to the second anode of a television picture tube.

In Figure 2, where parts shown in Figure 1 are designated by the same numerals, a lead 25 connecting the primary of the transformer 12 to the anode of the rectifier tube 14 is made with a diameter of approximately $\frac{1}{6}$ inch to avoid corona. The base 26 of the rectifier tube 14 is inserted into an octal socket 27 of the wafer type in common use in television receivers. The wafer socket is mounted on metallic posts 28 by means of screws 29. The posts 28 are supported in turn by the metallic cup-shaped member 21, and fastened thereto by the screws 32. This member 21 is preferably formed from aluminum sheet by a simple punching process well known to the fabrication art and as such can be mass produced at low cost. In the punching process the edge of the cup-shaped member 21 is preferably formed into a rounded lip 33 having a diameter of approximately $\frac{1}{8}$ inch to avoid corona.

The cup shaped member 21 is mounted on the chassis 34 by means of phenolic stand-off insulators 35 and screws 36, providing a compact, inexpensive, and highly desirable construction when assembled in accordance with the invention as will be more fully explained below.

The octal socket 27 contains eight base terminals 41-48 corresponding respectively to terminals 1-8 of standardized octal socket terminology. The elements and wires may be connected to the desired terminals before assembly of the socket 27 with the conductive member 21. The resistor 19 is connected between base terminals 42 and 46. The resistor 17 is connected between the terminals 44 and 47. The terminal 42 is also connected to the metallic post 28, forming thereby a conductive path between terminal 42 and the cup-shaped member 21. This last connection may be omitted if the leakage re-

sistance of the octal socket 27 is low compared to the resistance of the insulators 35, a condition which usually has been found to exist. Circuit elements connected to the tube socket, and operating at high potentials, are within the space enveloped by the cup-shaped element 21, thus avoiding the necessity of element corona shields.

The terminals 42 and 44 are connected to the secondary of the transformer 12 by means of the conductive wires 52 and 53, respectively. The terminals 42 and 46 are connected to filter capacitors 18 and 22 by means of conductive wires 54 and 55, respectively, the latter connection being made by connectors 56 which have a rounded external contour to prevent corona. For the same purpose the conductors 52-55 have a diameter of approximately $\frac{1}{8}$ inch. The filter capacitors 18 and 22 are connected rigidly by one terminal to the chassis.

The fundamental operation of the voltage supply is well known. An alternating voltage is applied to the grid 16 of the driving tube 15 causing a current from the source 13 to flow therein intermittently. When the current through the tube is cut off by the action of the grid, a high positive voltage peak occurs in the primary of the transformer 12 causing the filter capacitor to receive a positive charge through the rectifier tube 14. This charge is filtered of alternating current components by the action of the elements 19 and 22 and applied to a direct current load such as the second anode of a cathode ray picture tube. The resistor 17 may be chosen to provide desired power in the filament of the rectifier tube 14.

The operation of the conductive member 21 may be understood by referring to Figures 3, 4 and 5. In Figure 3, the conductive member 21 is charged up to a high positive direct potential during the operation of the set. Regions of successively lower potential surfaces are indicated by the lines 62. It will be noticed that the surfaces 34 and 21 tangent to the insulating members 35 are essentially parallel, the insulating members extending at right angles thereto, so that the equipotential surfaces pass through the supporting insulators at almost right angles to the axes thereof, thereby assuring a uniform potential gradient within the insulator. Under these conditions phenolic may be used as an insulating material without danger of progressing carbonization and ultimate destruction.

In Figure 4 there is shown an octal socket 27 mounted directly on stand-off insulators 35 without the use of the conductive member 21. The lines 62 in this figure, drawn approximately where the equipotential surfaces occur, tend to bunch around the protruding terminals of the socket as indicated by the numeral 63. The bunching of lines is indicative of a high potential gradient in this region. If a phenolic insulator is used, this high gradient is destructive, causing carbonization in the direction of the electric field. Once the carbonization commences, the process of destruction becomes cumulative, since the carbonized portions are conductive, forming high potential fields at their ends and causing "tentacles" of carbonized matter to grow at both ends, in the direction of the field. The growth of carbonized matter is shown in Figure 5, where the antlerlike carbon tentacles 64 are shown before the process of carbonization has resulted in complete destruction. The condition shown is typical of those found in television receivers where the conductive member 21 had been omitted. The

length of time required for complete destruction varied from several weeks to over a year, the reasons for the differences in time not being known, since the several sets had been made as similar to one another as was practical using ordinary production care. In all of these cases, no visible or audible indication of the destructive process was present until the last stages. By the addition of the conductive member 21, a potential gradient of 10 kilovolts per inch can be maintained for an indefinite period of time under a wide variety of temperature and humidity conditions.

In the preferred form shown, a phenolic insulator of homogeneous material is used. It is believed that stable operation under the high potential gradient here shown require this. If an insulator is formed of an aggregate of dissimilar materials, having differing dielectric constants or resistivities, there may occur local points of increased potential gradient, causing carbonization. Therefore it is believed advisable to use a homogeneous material.

Although a specific embodiment has been shown and described, other embodiments will be readily understood from the teachings above. The scope of my invention, therefore, will be best understood by referring to the following claims.

What is claimed is:

1. In a high voltage supply, a planar conductive surface substantially at ground potential, a homogeneous insulating member attached to and extending at right angles from said surface, a tube socket having terminals at high potentials, and a conductive member charged substantially to said high potentials partially enclosing said socket, said conductive member being supported by and having a surface adjacent said insulating member, said adjacent surface being essentially planar and parallel to said conductive surface.

2. In a high voltage supply, a planar conductive surface substantially at ground potential, a homogeneous insulating member attached to and extending at right angles from said surface, an insulating support for high potential circuit elements, and a conductive member charged to high potential partially enclosing said support, said conductive member being supported by and having a surface adjacent said insulating member, said adjacent surface being essentially planar and parallel to said conductive surface.

3. In a television receiver, a chassis, a direct current voltage supply comprising a source of alternating voltage, a rectifier tube connected in series with said source, a socket for said tube having high potential terminals, an electrically conductive member charged to high potential partially enclosing said socket, and a homogeneous insulating member supporting said conductive member and extending between said conductive member and said chassis, said chassis and conductive member being substantially planar and mutually parallel in the vicinity of said insulating member.

4. In a high voltage supply, a planar conductive surface substantially at ground potential, a homogeneous insulating member attached to and extending at right angles from said surface, and a conductive member supported by said insulating member and having a planar surface adjacent said insulating member essentially parallel to said conductive surface, said conductive member being charged to a potential in kilovolt units ap-

proximately ten times the length of said phenolic member in inches.

5. In a high voltage supply, an electrically conductive planar surface substantially at ground potential, a homogeneous insulating member attached to and extending at right angles from said surface, a conductive member supported by and having a surface adjacent said insulating member, said adjacent surface being essentially planar and parallel to said conductive surface, an aperture in said conductive member, an electrically conductive high-voltage junction structure partially enclosed within and connected to said conductive member, and conductive wires attached to said junction structure and extending through said aperture.

6. In a television receiver, a chassis, a direct current supply comprising a source of alternating voltage, a rectifier tube connected in series with said source, a socket for said tube, a circuit element at high potential connected between terminals of said socket, a conductive member partially enclosing said socket and said element and charged substantially to said high potential, and

a homogeneous insulating member supporting said conductive member and extending between said conductive member and said chassis, said chassis and conductive member being substantially planar and mutually parallel in the vicinity of said insulating member.
